UNITED STATES PATENT OFFICE.

MEREDITH G. STANLEY, OF CINCINNATI, OHIO, AND ARTHUR EARL BOWMAN, OF COVINGTON, KENTUCKY.

RECEIPTING STAMP AND REGISTER.

1,311,189.

Specification of Letters Patent. Patented July 29, 1919.

Application filed September 12, 1918. Serial No. 253,821.

To all whom it may concern:

Be it known that we, MEREDITH G. STANLEY and ARTHUR EARL BOWMAN, citizens of the United States, and residing at Cincinnati and Covington, in the counties of Hamilton and Campbell, and States of Ohio and Kentucky, respectively, have invented a new and useful Receiving Stamp and Register, of which the following specification is a full disclosure.

This invention relates to a type setting hand stamp for making duplex impressions, one impression upon a record strip housed within the casing of the device.

An object of the invention is the production of simple and efficient feeding devices for the record web and inking ribbon which will advance both record strip and inking ribbon after each impression, allowing each impression to be successively recorded upon the web, and operated by a full stroke lever device which in conjunction with said feeding devices operates a platen for making the impression upon the record web and upon a sheet of paper or the like, inserted upon the platen.

Other objects and features of the invention relate to details of construction and arrangement of parts more fully set forth in the description of the accompanying drawings forming a part of this specification, and in the drawings, like characters of reference denote corresponding parts throughout the several views of which:—

Figure 1 is a side elevation of our improved hand stamp, of a size for the user to carry in his pocket.

Fig. 2 is a plan view of the base plate of printer and recorder casing showing the paper and inking ribbon roll supported and journaled thereon.

Fig. 3 is a central vertical section through the device shown in Fig. 1.

Fig. 4 is a side elevation of the mechanism disposed along and within the side of the casing for feeding and rewinding the paper.

Fig. 5 is an opposite side elevation of the mechanism for feeding the inking ribbon.

The stamp embodies the general principles of construction disclosed in a prior patent to Meredith G. Standley, No. 1,233,520 dated July 17, 1917, relating to the mounting and arrangement of the record strip and inking ribbon rolls relative to one another and to the printing wheel, with the invention here-

in directed particularly for operating mechanism for the record strip, the inking ribbon rolls, and the printing platen.

Referring to the drawings and to Fig. 1 inclusive, 1 indicates a casing of rectangular form for a pocket size hand stamp having a platen 2 hinged thereto below the base 3 of the casing. The base 3 has a plate at one end is hingedly mounted upon a cross or pivot rod 4 supported in the side walls of the casing 1 and is arranged to swing outward for access to the interior of the casing. The opposite end of the base or plate 3 carries latch devices for engaging with lock devices supported and housing within rear end of the casing. The platen 2 is hingedly mounted upon pivot rod 4 with the base 3. A spring 5 is interposed between the base 3 and platen 2 at the fulcrumed ends and fixed to the platen for forcing the platen outwardly from the base providing a normally open throat for receiving the paper upon which an impression is to be made by the type wheels 6, Fig. 3. The type or printing wheels 6 are rotatably mounted with the casing and arranged to project through an opening in a plate or shelf 7 fixed within the casing and also through an opening in the bottom plate 3.

The wheels are operated by means of rack bars 8 slidably supported between the plate 7 and top wall of the casing, and are provided with knobs 9 projecting through slots 10 for operating the wheels 6 to bring the type characters into and out of a printing position. The rack bars having indicatory characters on their upper surfaces, which are exposed, corresponding to the type characters on the type wheels for setting purposes, when a rack bar is moved to expose a given character thereon through the slot 10 in the top wall of the casing. The bottom or base plate 3 at opposite side of the type wheels is provided with suitable bearing extension for supporting and journaling the spindles 11—12 for the inking ribbon 13 and the spindles 14—15 for the record strip 16.

The inking ribbon is fed with each printing operation, from one spindle and rewound on the other. The feeding mechanism being arranged to be shifted to alternate the direction of the ribbon feed. The spindle 14 for the record strip may be designated as the supply spindle from which the record strip is unwound while spindle 15

may be designated as a rewind spindle for receiving the unwound strip from spindle 14. The strip from 14 passes over a guide or cross rod 17, thence over that periphery portion of the type wheels which project through an opening in the base plate 3, so that it directly contacts the printing characters in this printing position. The inking ribbon passes from one spindle to the other 10 through the apertures 18-19 in the base plate 3 and over the record strip at a point diametrically with the type wheels. This record strip is transpicious, making the impression on one side legible through the 15 strip from the other side. An impression is also made upon a card or sheet of paper inserted upon the pad 20 upon the platen 2 when the platen is moved or swung against the type wheels. In the aforesaid prior patent this is accomplished by pressing the casting and platen together. With the present invention the platen is swung toward the type wheel by full stroke lever mechanism, and which also controls and actuates the record web and inking ribbon feeding devices. 20

A hand lever 21, exterior of the casing 1, is fixed upon one end of a rock shaft 22 journaled in the side walls of the casing and having one end projecting exteriorly beyond 30 a side wall to receive said handle. Fixed upon the rock shaft 22 within the casing is a ratchet wheel 23 having right and left sets of ratchet teeth 24-25 upon its periphery and at a suitable spaced relation to alternately 35 coöperate with the crescent shaped pawl 26 swiveled upon a side wall of the casing; see Fig. 3. The ratchet wheel between the two sets of teeth has a tooth 27 radiating therefrom adapted, as the ratchet wheel is rotated, to engage with either of the opposite cam edges 28 of the U-shaped cam plate 29 fixed upon the pawl 26. The action of the tooth 27 when engaged with the cam plate 29 swings the cam plate as an escapement to 40 throw one pawl tooth out of engaging position with a relative set of ratchet teeth and throws the other into engagement with the opposite set of ratchet teeth. Such operation taking place at the end of a crank throw 45 of the hand lever 21, so that a full throw or stroke of the hand lever in one direction must be made before it can be reversed. A V-lug 30 projects from the rear of the pawl engaging with a spring 31 depending from 50 the plate or shelf 7 for forcing a pawl tooth into engagement with its relative set of ratchet teeth of the ratchet wheel. The V-lug 30 has its apex diametrical with the axis of the pawls and the spring 55 engages alternately upon the inclined surfaces of the lug bringing the spring form at opposite side of a dead central position. For a more definite understanding and with the parts in their positions shown in Fig. 3, it will be observed that 60

the pawl 26 is engaged with the ratchet teeth 24 locking the ratchet wheel 23 against motion in a reverse direction. The rotation of the ratchet wheel in a forward direction must be continued until the tooth 27 engages 70 with and throws the pawl to its opposite position bringing it into engagement with the set of ratchet teeth 25, which locks the ratchet wheel as soon as its teeth are engaged against further forward rotation under 75 which condition the ratchet wheel can only be revolved in a reverse direction until the pawl has again been tripped.

Platen actuating mechanism.

The platen 3 about intermediate of its length and at opposite sides thereof is provided with a pair of lugs or ears 32-32 carrying the cross rod 17 which also serves as a guide for the record strip. The cross rod 85 17 extends across the width of the casing 1 and engages into a cam notch 33 formed in each of the slide plates 34-34^a, slidably mounted upon the opposite side walls 36-36^a adjacent the respective side walls of the 90 casing 1. Each slide plate is provided with a pair of longitudinal slots 35-35, each having a headed stud or pin engaged therethrough and fixed to a side wall 36 or 36^a. Thus as the slide plates 34-34^a are moved 95 in an appropriate direction the cross rod 17 is engaged into the notches 33 of the slide plates and against the cam surfaces on the slide plates formed by the notches, which surfaces are inclined in a direction to draw 100 the platen toward the face plate 2 of the casing to bring the impression pad into engagement with the type wheels. Each notch 33 is of an outline to provide a longitudinal shoulder or edge surface 37 engaging with the cross rod when the platen is in its normal position, preventing the platen from being depressed, unless the slide plates are shifted. 105

Each slide plate 34-34^a connects with the rock shaft 22 by means of a crank arm 38 110 fixed upon said shaft and pivotally connected to a link 39 which link pivotally connects with its companion slide plate. Thus as the shaft is rocked the slide plates are shifted for swinging the platen toward or 115 from the type wheels.

Record web feeding mechanism.

The slide plates 34-34^a aside from actuating the platen are respectively employed for 120 operating the web and inking feeding mechanism, one slide plate carrying the mechanism, feeding the web, and the other carrying the mechanism for feeding the inking ribbon. The web feeding mechanism is 125 shown in Fig. 4 and consists of a spring tensioned pawl 40 pivoted upon the slide plate 34 having its hook or toothed end engaged with a ratchet wheel 41 fixed on the web rewinding spindle 15. A spring 42 fixed to the 130

slide plate 34 connects to the opposite end of the pawl for forcing its toothed end downward into engagement with the ratchet wheel 41. Thus on each left or return stroke of 5 the slide, the pawl will rotate the ratchet wheel 41 and web rewinding spindle 15 to advance the web sufficiently to bring a successive or clear printing space beneath the type wheel. The side wall 36 is slightly 10 spaced from its adjacent casing wall with the pawl 40 mounted on the outside surface of said wall within said space so as to be bound between the casing wall and slide carrying wall.

15 *Inking ribbon feeding mechanism.*

The inking ribbon feeding mechanism is shown in Fig. 5 and mounted upon the slide plate 34^a. It consists of a pair of spring 20 tensioned pawls 44—45 each pivoted upon the slide plate 34^a with the pawl 44 arranged and located to engage with the ratchet wheel 46 on the spindle 12 for rotating the spindle in step motions as the pawl is moved in one 25 direction with the slide plate. A spring 47 fixed upon the slide plate is connected with the pawl for forcing the pawl toward the ratchet wheel. The second inking ribbon spindle 11 at a side opposite of the type 30 wheels from that of the spindle 12, likewise is provided with a ratchet wheel 48 engaged by the pawl 45 for rotating said spindle 12 in a step motion with each return stroke of the slide plate 34^a. This pawl 45 has a 35 spring 49 connected thereto and to the slide plate for yieldingly forcing the pawl toward the ratchet wheel. The pawls 44 and 45 each are provided with a crank arm 50, each arranged to engage with a respective stop pin 40 projecting from the slide plate 34^a to limit the swing of their respective pawls in one direction. The direction of ribbon feed may be alternated by tripping the pawls 44 or 45 so as to unwind from one spindle and rewind 45 upon the other. A trip or shifter plate 51 is slidably mounted upon the slide plate 34^a provided with a finger 52 at each of its opposite ends, one finger for engaging the crank arm 50 of the pawl 44 and the other 50 for alternately engaging the crank arm of the pawl 45 to swing and maintain the disengaged pawl in a released position out of engagement with its pawl. As shown in Fig. 5 the trip plate 51 has its finger projecting from the left and engaged with the crank arm of pawl 44, having swung it sufficiently to raise its pawl toothed end upwardly above and away from contact with the ratchet wheel 46. The pawl 45, with 55 the trip plate 51 in such position, is free to engage the ratchet wheel 48. With each stroke of the slide plate 34^a to the right or reverse stroke, the pawl 45 rotates the ratchet wheel 48 appropriately for a determined 60 length or ribbon advance, unwinds the rib-

bon from spindle 12 and rewinds it upon spindle 11. Sliding the plate 51 to an opposite position, places pawl 44 in commission while throwing out pawl 48, resulting in an alternate direction of ribbon feed with each 70 right or reverse stroke of the slide plate so that a new inking ribbon space is presented to the type wheels after an impression has been made. The upper edge of the shifter plate 51 is notched to receive the catch end 75 of the spring 54 for retaining the plate in its adjusted positions.

The device as above described is complete in itself as a pocket or portable lever operated hand stamp, and in this form is placed 80 within and operated as a cabinet or desk machine by disconnecting the hand lever 21 from the rock shaft and slipping the stamp frame or casing 1 within an auxiliary frame, as shown in Figs. 1 to 10 inclusive, for mounting within a cabinet or desk. The cabinet mechanism is also capable of receiving and operating the type of hand stamp shown in Letters Patent No. 1,206,766 to M. G. Standley and C. W. Gosnell Nov. 28, 1916, and No. 1,206,735 to M. G. Standley Nov. 28, 1916, in which the platen is manually depressed 85 against the type wheels.

Having described our invention, we claim:—

1. A stamp comprising a box-like casing, printing wheels journaled therein and projecting through an orifice in the base of the casing, an inking ribbon supported at opposite sides of the printing wheels and passing 100 over the type characters of said wheels at the casing base opening, a platen hingedly mounted upon the casing adjacent the casing base adapted to be pressed against said printing wheels, reciprocating slide members 105 respectively mounted upon opposite side walls of the casing arranged to engage with and swing said platen, and lever devices for reciprocating said slide members.

2. A stamp comprising a box-like casing, 110 printing wheels journaled therein and projecting through an orifice in the base of the casing, an inking ribbon supported at opposite sides of the printing wheels and passing over the type characters of said wheels 115 at the casing base opening, a platen hingedly mounted upon the casing adjacent the casing base adapted to be pressed against said printing wheels, reciprocating slide members respectively mounted upon opposite side walls 120 of the casing for swinging said platen, means on one of said slide members for feeding said ribbon with each return stroke of said slide member, and means for reciprocating said slide members.

3. A stamp comprising a box-like casing, printing wheels journaled therein and projecting through an orifice in the base of the casing, inking ribbon supports at opposite sides of the printing wheels, an inking rib- 130

- bon upon said supports passing from one to the other, across the type characters of said wheels at the casing base opening, record web supports at opposite sides of the printing wheels, passing a record web from one support to the other between the inking ribbon and printing wheels, a platen hingedly mounted upon the casing adjacent the casing base adapted to be pressed against said printing wheels, reciprocating slide members respectively mounted upon opposite side walls of the casing for swinging said platen, inking ribbon feeding means mounted on one slide member for advancing said inking ribbon with each corresponding stroke of said slide member, and web feeding means mounted on the other of said slide members for advancing said web with each corresponding stroke of said second slide member.
- 20 4. A stamp comprising a box-like casing having a base hinged to swing outwardly, a platen hinged to the casing adjacent the base, printing wheels mounted in said casing and projecting through an opening in said base, record strip supports mounted on said base at opposite sides of the printing wheels for passing a record strip from one support to the other over the periphery of
- the printing wheel at said base opening, inking ribbon supports mounted on said base at opposite sides of the printing wheels for passing an inking ribbon from one support to the other to contact with said record strip at the printing wheels, reciprocating slide members respectively mounted upon opposite side walls of said casing, for operating said platen for swinging and pressing the same against said printing wheels for making an impression on said record strip, full stroke lever actuated crank devices connecting with said slide members for reciprocating the same, inking ribbon feeding means mounted on one of said slide members, adapted to advance said ribbon with one slide stroke, record strip feeding means mounted on the record slide member adapted to advance said strip with one slide stroke.

In witness whereof, we hereunto subscribe our names, as attested by the two subscribing witnesses.
